[57] CLAIM

The ornamental design for clock face, as shown and
described.

DESCRIPTION

FIG. 1 is a top and right front perspective view of a
clock face showing my new design;
FIG. 2 is a typical side elevational view thereof;
FIG. 3 is a rear elevational view thereof; and
FIG. 4 is a rear elevational view of another embodiment
of my new design of FIGS. 1-3, the broken-line show-
ing being for environmental purposes only and forming
no part of the claimed design.
